UNITED STATES PATENT OFFICE.

LEO J. SCHAEFER, OF TOLEDO, OHIO.

RUBBER HEEL.

1,383,155.

Specification of Letters Patent. Patented June 28, 1921.

Application filed December 26, 1919. Serial No. 347,304.

To all whom it may concern:

Be it known that I, LEO J. SCHAEFER, a citizen of the United States, and a resident of Toledo, in the county of Lucas and State 5 of Ohio, have invented a certain new and useful Rubber Heel; and I do hereby declare the following to be a full, clear, and exact description of the invention, such as will enable others skilled in the art to which it 10 appertains to make and use the same, reference being had to the accompanying drawings, and to the characters of reference marked thereon, which form a part of this specification.

15 My invention relates to removable rubber heels and it has for its object to provide a means for readily connecting and disconnecting replaceable heels to and from a shoe and also to provide in such a heel a means 20 whereby the heel will be uniformly resilient throughout the supporting surface.

Details of my invention may be varied in form without departing from the spirit thereof. To illustrate a practical application 25 of the invention I have selected one form of rubber heel containing the invention. The particular form selected is illustrated in the accompanying drawings.

Figure 1 illustrates a top view of the heel 30 having a circular retaining member. Fig. 2 illustrates a top view of the same heel having an oblong retaining member. Fig. 3 is a transverse sectional view taken on the line 3—3 indicated in Fig. 1.

35 1 in the figures is a rubber heel. It is provided with a circular recess 2 into which extends a returned portion or flange 3. A channel 4 that is thus formed is thus located about midway between the upper and lower 40 surfaces of the heel. The heel is also provided with a portion 5 that protrudes into the recess 2 and is of a size that leaves a considerable area about the protuberance within the recess 2. The protuberance 5 thus 45 forms an annular recess within the heel. The protuberance 5 also has a recess 6 to increase the resiliency of the protuberance 5 and consequently of the heel as a whole. The protuberance 5 thus resiliently supports

50 the central portion of the heel and by reason of the relation of its size to the size of the recess 2 and also by reason of the recess 6 it produces resiliency in the heel and at the same time supports the supporting surface 55 of the heel. A retaining member 7 is attached to the bottom of the shoe by any

suitable means such as by the brads or nails 8. The retaining member 7 is preferably formed of sheet metal having a surface 9 that corresponds and fits the surface of the 60 shoe above the heel portion. The retaining member 7 has a flange 11 that extends away from the shoe and the edge of the flange is curved or spun so as to form a relative large bead 10 extending around the outer edge of 65 the flange. The bead 10 is so located that the inwardly extending flange 3 of the heel will snugly fit beneath the bead 10. The bead 10 is thus located in the channel 4 and its size relative to the size of the channel 4 70 is such as to leave considerable room for the movement of the rubber beneath and at the side of the bead 10. By this arrangement the bead does not compress the rubber, but the supporting portion of the heel is allowed free play to permit its resiliency to act 75 in forming a cushion for the wearer when walking. Also the protuberance 5 extends to the top of the inverted cup shape retaining member 7 and makes contact therewith on the annulus formed about the recess 6.

The heel is secured by forcing the flange 3 above the bead 10 until the bead enters the channel 4. As the heel wears it may be turned about the retaining member 7 to 85 bring less worn portions in that position of the heel where most wear is produced, that is, at the back of the heel and usually at one or the other side at the back.

The cup shaped retaining member 7 may 90 be made cylindrical in form or it may be made oblong as indicated in Fig. 2. The heel itself may be made cylindrical in form and stretched over the longer axis of the retaining member. The heel will then be ob- 95 long in form and will conform more accurately to the shape of the bottom surface of the ordinary heel, particularly at the back and sides. The heel, although stretched to form an oblong heel may also be rotated 100 about the oblong retaining member owing to the elasticity of the rubber of which the heel is formed in order that portions of the heel may be placed at the back where most of the wearing is performed.

In order to prevent the flange 3 from being pulled over the bead particularly in the oblong form of the heel shown in Fig. 2, angular strips 12 are located in spaced relation about the flange 3. The upper inturned 110 ends 13 press against the bead and tend to hold the lower side portion 14 against the

shoe. The upturned ends 15 engage in the rubber and thus the heel is held against the shoe notwithstanding the pull caused by stretching of the rubber.

5 I claim:—

In a rubber heel, a retaining member having a beaded flange around its lower edge, the rubber heel having a recess and an inwardly extending flange, the flange fitting

around the outside of the retaining member 10 and above the bead and angular retaining strips secured to the heel and having parts thereof located on the outside of the flange to form a bearing surface against the upper side of the bead.

15 In testimony whereof I have hereunto signed my name to this specification.

LEO J. SCHAEFER.
